UNITED STATES PATENT OFFICE

BUICHI MORISHITA, OF LOS ANGELES, CALIFORNIA

NURSING BOTTLE HOLDER

Application filed December 24, 1929. Serial No. 416,236.

This invention relates to an improved device for holding a nursing bottle, and its objects are to provide elements capable of holding a nursing bottle in a position whereby an infant may readily and conveniently consume the contents of the bottle without attention by an older person.

Heretofore, nursing bottles have been provided with a nipple on the end of a long rubber tube leading from the bottle. The long rubber tube has proven unsanitary and more or less inconvenient in use.

To avoid these objections, I have provided an efficient holder for the nursing bottle, having several means of adjustment whereby the bottle may be set and retained in any desired position and in convenient reach of an infant while in a carriage, or on a bed, cot, or other similar device.

The drawings illustrate an embodiment of the invention which I have so far found to be the most practical in use, and in which—

Figure 1 is a perspective view of the holder having a bottle therein. Fig. 2 is a detail view of the upper clamp member. Fig. 3 is a detail view of the upper adjusting element. Fig. 4 is a perspective view of the bottle clamp. Fig. 5 is a detail view of a clamp for securing the device to a bed, cot, or carriage. Fig. 6 is a detail plan of the belt element. Fig. 7 is a side elevation of the clamp for securing the device to a bed, cot, or carriage.

Referring in detail to the drawings, the holder consists of a spring wire bail 11, having on each extremity the clamp members 12, adapted to rest upon or engage with a bed, cot, baby carriage, or other similar device. Clamp members 12, are pivotally mounted on pivot pins 13, on the extremities 40 of bail 11. A cloth fabric belt 14 is secured to the extremities of bail 11, and is adapted to pass beneath the infant when the device is in use. A clamp member 15 is slidable on bail 11, and has a clamping screw 16, 45 whereby it may be clamped in any desired

position. The upper suspending member 17 is slidable through the clamp member 15, and is secured in position by a screw 18. Member 17 is formed with a loop portion 19, and the bottle clamp 20 is slidable on the loop portion, and is secured in position by a screw 21. Bottle clamp 20 has a loop portion 22 to engage with the neck portion of a nursing bottle 23, and has a loop portion 24 to pass around the body portion of the bottle. Another loop member 25 is loosely mounted on loop portion 24, and is adapted to pass over the bottom of the nursing bottle.

In use, the device is positioned upon a baby carriage, bed, cot, or similar device, and the belt is passed beneath the infant. A nursing bottle is then positioned in the bottle clamp, and the device is then adjusted whereby the bottle will be within convenient reach of the infant. Each clamping screw may be loosened for a sliding adjustment, or swivel adjustment, or angular adjustment of the corresponding part of the device. The bottle clamp is adapted for suspension of any ordinary style of nursing bottle.

From the foregoing description and the drawings, it may be seen that I have provided a nursing bottle holder, having a practically universal adjustment for securing and maintaining a nursing bottle in any desired position relative to an infant which is to be fed from the bottle.

What is claimed is:

1. A nursing bottle holder, comprising a bail member, a cloth fabric belt extending between the extremities of the bail member, clamp elements on the extremities of the bail member, a suspending member adjustably secured to the bail member, and a nursing bottle clamp adjustably secured to the suspending member.

2. A nursing bottle holder, comprising a bail member, a cloth fabric belt extending between the extremities of the bail member, a clamp member slidable on the bail member,

means for clamping said clamp member in position on the bail member, a suspending member mounted in said clamp member, and a nursing bottle clamp adjustably secured to the suspending member.

3. A nursing bottle holder, comprising a bail member, a fabric belt secured to the extremities of the bail member, suspending elements adjustably secured to the bail member and between the extremities thereof, and a nursing bottle holder adjustably secured to the suspending elements.

In testimony whereof, I hereunto affix my signature.
